CLAIM

The ornamental design for a roof tent frame, as shown and described.

DESCRIPTION

FIG. 1 is a top, front, left perspective view of a roof tent frame showing our new design, in an open position;

FIG. 2 is a bottom front, left perspective view thereof, in an open position;

FIG. 3 is a perspective view thereof, in a closed position;

FIG. 4 is a front elevational view thereof, in an open position;

FIG. 5 is a left side elevational view thereof, in an open position;

FIG. 6 is a rear elevational view thereof, in an open position;

FIG. 7 is a right side elevational plan view thereof, in an open position;

FIG. 8 is a top plan view thereof, in an open position; and,

FIG. 9 is a bottom plan view thereof, in an open position. The broken lines illustrate portions of the roof tent frame which form no part of the claimed design.
